WARREN F. CLEMENTS, OF ALLENSTOWN, PENNSYLVANIA, ASSIGNOR TO FULLER LEHIGH COMPANY, OF FULLERTON, PENNSYLVANIA, A CORPORATION OF DELAWARE

GRINDING BALL

Application filed March 6, 1929. Serial No. 344,700.

This invention relates to grinding balls and the process of making them for use in mills for grinding material such as coal, for example, in which balls are pushed around over a grinding surface.

The invention will be understood from the description in connection with the accompanying drawings in which Fig. 1 is a side view of half of a mold in which the balls are cast, showing a ball in section; and Fig. 2 is a section along the line 2--2 of Fig. 1.

In the drawings reference character 1 indicates half or one side of a mold that may be made of cast iron that is made in two halves that can be clamped or bolted together. Each half of the mold is provided on its inner face with a hemispherical opening 2 into the lower side of which a groove or passageway 3 for molten material leads from the upper side 4 of the mold. A riser 5 extends from the upper edge of the spherical opening 2 along the inner face of each half of the mold to the upper surface of the mold. When the halves of the mold are put together they enclose the spherical opening into which metal for forming the ball can be introduced through the inlet or groove 3.

Recesses 6 are provided in the inner faces of each half of the mold around the edges of the hemispherical openings, so that a previously cast spider 7 with arms 8, having the ends thereof extending into said recesses 6, can be put in place before the halves of the mold are put together. The spider 7 may also be provided with shorter arms 9, extending at right angles to the plane of the arms 8.

In producing the balls, the spider 7, which is preferably made of grey iron, is put in place with the ends of its arms 8 extending into the recesses 6, the two sides of the mold assembled and molten iron is poured through the inlet 3 filling the spaces in the spherical opening around the spider 7 and arms 8 and 9. This molten iron may be of silica iron that will become chilled to a certain extent in the mold as it solidifies and knits around the spider 7 and arms 8 and 9. The mold is then opened and the protruding ends of the arms

8 removed to leave a smooth spherical surface.

It has been found that when a metal casting or spider is used as described above around which the ball is poured, no large mass remains hot at the center after the surface is cooled, with the result that there are less internal strains in the ball as a whole when it is finished, which makes it less liable to break when used as a grinding ball.

I claim:

1. A grinding ball having an inside spider of soft iron and the remainder of hard iron, said spider having arms extending into said hard iron.

2. A grinding ball having an inside spider of grey iron and the remainder of silica iron, said spider having arms extending into said silica iron.

3. A grinding ball having an inside spider of soft iron and the remainder of hard iron, said spider having arms, the ends of which terminate at the surface of said ball.

4. A grinding ball having an inside spider of soft iron and the remainder of hard iron, said spider having radial arms some of which terminate at the surface of said ball.

WARREN F. CLEMENTS.
